CLAIM

The ornamental design for a manual power transfer switch, as shown and described.

DESCRIPTION

FIG. 1 is a top, front, right side perspective view;
FIG. 2 is a front elevation view;
FIG. 3 is a rear elevation view;
FIG. 4 is a left side elevation view;
FIG. 5 is a right side elevation view;
FIG. 6 is a top plan view;
FIG. 7 is a bottom plan view; and,
FIG. 8 is a top, front, right side perspective view shown in an environment.

In FIGS. 1 through 8, the broken lines are for the purpose of illustrating portions of the manual power transfer switch that forms no part of the claimed design. However, in FIG. 8 the broken lines also show an environment. In the drawings, no broken lines form any part of the claimed design.
